[57] **CLAIM**

The ornamental design for a pick-up truck cover mounting clamp, as shown and described.

DESCRIPTION

FIG. 1 is a perspective view showing the top, rear end and side of a pick-up truck cover mounting clamp illustrating my new design;

FIG. 2 is a rear end elevation view of the pick-up truck cover mounting clamp of FIG. 1;

FIG. 3 is a front end elevational view thereof;

FIG. 4 is a side elevational view of the side shown in FIG. 1;

FIG. 5 is a side elevational view showing the side opposite that shown in FIG. 4;

FIG. 6 is a top plan view thereof; and,

FIG. 7 is a bottom plan view thereof.

FIG. 1

FIG. 2

FIG. 3

FIG. 4

FIG. 5
